(57) **CLAIM**

The ornamental design for a bag closure as shown and described.

DESCRIPTION

FIG. 1 is a front view in a closed status of a first embodiment of a bag closure, showing the new design;

FIG. 2 is a rear view in a closed status thereof;

FIG. 3 is a perspective front view in a closed status thereof;

FIG. 4 is a right side view in a closed status thereof, a left side view being a mirror image thereof;

FIG. 5 is a top view in a closed status thereof;

FIG. 6 is a front view in an opened status thereof;

FIG. 7 is a perspective front view in an opened status thereof;

FIG. 8 is a right side view in an opened status thereof, a left side view being a mirror image thereof;

FIG. 9 is a front view in a closed status of a second embodiment of a bag closure, showing the new design;

FIG. 10 is a rear view in a closed status thereof;

FIG. 11 is a perspective front view in a closed status thereof;

FIG. 12 is a right side view in a closed status thereof;

FIG. 13 is a left side view in a closed status thereof;

FIG. 14 is a front view in an opened status thereof;

FIG. 15 is a rear view in an opened status thereof;

FIG. 16 is a perspective front view in an opened status thereof; and,

FIG. 17 is a left side view in an opened status thereof.

Broken lines depict portions of the bag closure or environmental structure that form no part of the claimed design.

1 Claim, 17 Drawing Sheets
